DANIEL M. NIXON, OF DANVILLE, ILLINOIS.

Letters Patent No. 87,281, dated February 23, 1869.

IMPROVED BRIDLE-BIT.

The Schedule referred to in these Letters Patent and making part of the same.

To all whom it may concern:

Be it known that I, DANIEL M. NIXON, of Danville, county of Vermilion, State of Illinois, have invented a new and improved Bit for Bridles; and I hereby declare the following to be a full, clear, and exact description thereof, which will enable others skilled in the art to make and use the same, reference being had to the accompanying drawings, making a part of this specification, in which—

Figure 1 is a top view.

Figure 2 is a side elevation.

Figure 3 is a top view of the bar of the bit, which contains the socket.

Similar letters of reference indicate corresponding parts.

My invention consists in uniting the bars of bridles bits by means of a ball-and-socket joint, as will be hereinafter more fully described.

The bar A, in the drawings, contains the socket A', which is located at its inner extremity.

That portion of the bar which contains said socket is somewhat flattened, and is turned at a considerable angle from the arm of the bar.

The arm of the bar is circular, or of any desired form, and is slightly curved throughout its length.

A' is the socket, above referred to. It is oblong, and is bevelled on its face, so as to permit the ball on bar B to fit closely into it. It is large enough to allow the arm of bar B to slide freely within it.

Bar B carries, on its inner end, the ball B'. Its arm is similar in construction to that of bar A.

B' is a ball, constructed on the bar at the point above stated. It is of the shape of a truncated cone,

the base of said cone coinciding with or forming the end of the bar, and the sides encircling the arm of said bar.

C are rings, passing through the outer ends of the bars, to which the reins are secured.

It is evident that the form of the ball, as well as that of the other portions of the bit, may be considerably varied, without affecting any result.

As the bars of a bit of this kind may be cast in form so as to be united by passing the arm of bar B through the socket A', it is apparent that a very strong joint is made—one that has very great advantages over those in common use.

If it were possible to twist the bit in the animal's mouth, so as to get the same purchase on the eye that can be had in bits of ordinary construction, the eye, being cast closed, is much stronger, and will endure such strain much better, than an eye which is closed by welding; but the arm B rotates freely in the socket A', so that twisting is impossible, and no leverage can be had which is sufficient to break the bars of the bit.

Having thus described my invention,

What I claim as new, and desire to secure by Letters Patent, is—

A bit, having its bars united by means of a ball-and-socket joint, substantially as shown and described.

In testimony whereof, I have signed my name to this specification, in the presence of two subscribing witnesses.

DANIEL M. NIXON.
